UNITED STATES PATENT OFFICE.

CHARLES Y. KNIGHT, OF CHICAGO, ILLINOIS, ASSIGNOR TO EDMUNDS & JONES CORPORATION, OF DETROIT, MICHIGAN, A CORPORATION OF NEW YORK.

ELECTRIC SWITCH.

Application filed December 6, 1923. Serial No. 678,797.

To all whom it may concern:

Be it known that I, CHARLES Y. KNIGHT, citizen of the United States, residing at Chicago, Illinois, have invented certain new and useful Improvements in an Electric Switch; and I do hereby declare the following to be a full, clear, and exact description of the invention, such as will enable others skilled in the art to which it appertains to

make and use the same.

My invention relates to electric switches of the so-called single-pole type, and in general aims to provide an unusually inexpensive, compact and durable switch of this class.

In one of its more particular objects, my invention aims to provide a switch in which a yieldingly mounted circuit-closing element forms part of a slidably mounted switching member, in which the yielding pressure is provided by a spring through which no current passes, in which the circuit-closing element continuously engages one of the contact terminals of the switch and is latched in either its "on" or "off" position by riding over a hump on this contact terminal, in which the circuit-closing is effected by the bridging of a plunger-tip across the gap between two contact terminals, and in which simple and effective means are provided for preventing the switching member as a whole from rotating.

Still further and also more detailed objects will appear from the following specification and from the accompanying drawings, in which—

Fig. 1 is a front elevation of an electric switch embodying my invention.

Fig. 2 is an enlarged section taken through the same switch centrally and transverse of its face, this being taken with the switching member in its circuit-exposed closing or "on" position.

Fig. 3 is a section similar to a portion of Fig. 2, but showing the switching member in its circuit-opening or "off" position.

Fig. 4 is a section taken along the line 4—4 of Fig. 2.

Fig. 5 is a perspective view of the digitally movable button which forms the exposed head of the movable switching member, showing the inward projection on this button which is engaged by walls of a slot to prevent the button from rotating.

In the embodiment of the drawings, the

switch of my invention comprises a cylindrical casing 1 provided at its forward end with ears 2, which ears are secured in any suitable manner to a face plate 3. This face plate forms the front of the switch and closes the forward end of the casing, while the rear end of the cylinder 1 is closed by an insulating disk 4 which forms the base of the switch.

Extending through and clinched to this insulating base 4 are a pair of hollow rivets 5 and 6, each of which is threaded for receiving one of the screws 7 and 8 as employed respectively for clamping the ends of the two circuit wires 9 and 10 to the said hollow rivets, so that these hollow rivets form portions of the circuit terminals.

Each of these hollow rivets has an enlarged head at its forward end and the head 11 of the rivet 5 projects over the edge of 75 a recess 12 formed in the forward face of the insulating base 4. The shank of the companion hollow rivet 6 extends through a perforation in a metal plate 14 which bears against the forward face of the insulating base and which has a channel-sectioned portion 15 formed from it and disposed within the said recess 12 to afford a contact terminal adapted to be engaged by the switching member of the switch.

The face plate 3 of the switch has a slot 16 extending in the same general direction as the channel-skated contact portion 15 of the said plate and disposed with the center of the slot opposite the center of this contact portion, so as to form a guide for the movable switching member hereafter described. Extending into this slot 16 is a portion 17 on the back of a button 18 which is exposed on the front of the face plate 3, 95 this extension 17 being in the form of a boss 17 having flat sides engaging the side walls of the slot 16 so as to keep the button from rotating in this slot. The button 18 serves as a sliding support for a cylinder 19 which 100 has a shank 20 threaded into the back of the button 18. An insulating washer 21 is interposed between the back of the face plate 3 and the forward end of this cylinder 19, but the boss 17 engages this washer and is 105 of a length greater than the thickness of the face plate 3, so as to prevent the screwing of the shank 20 into the button from clamping the face plate tightly between the washer 21 and this button. The cylinder 19 serves 110

as a carrier for a plunger having a head 22 slidably fitting the bore of the cylinder and continuously pressed forward by a spring 23. This plunger has a stem 24 projecting beyond the rear end of the cylinder and continuously engaging the channel or contact portion 15 of the said circuit terminal.

With the parts thus arranged, the cylinder 19 together with its spring-pressed plunger 10 and with its shank 20 extending through the slot in the face plate and with the insulating parts 21 and 18 disposed at opposite sides of this plate forms a bodily movable switching member which can freely be slid 15 longitudinally of the said slot so as to move the spring-pressed plunger 24 along the channel 15. The spring 19 maintains the tip of the plunger continuously in engagement with the channel 15 and this channel desirably is forwardly bowed so as to present a hump which will exert a cam action tending to hold the switching member either in its lowermost position (or "off") of Fig. 2 or in its uppermost (or "on") position in 20 Fig. 3. When in the former position, the plunger also contacts with the head 11 of the rivet 5, thereby bridging the gap between this head and the metal channel and hence closing the circuit connection between 25 the wires 9 and 10. When the switching member is in its uppermost position as shown in Fig. 3, the plunger is out of engagement with the lower rivet, thereby opening the circuit.

35 By thus bowing the bottom of the channel 15 so as to form a hump over which the plunger rides, I cause the switch to give a slight snap when moved in either direction, and in practice this snapping action is some- 40 what augmented by the usual looseness of the fit of the plunger head 22 within the cylinder 19. Consequently, my novel switch construction affords a positive throw-over for the switching member whenever this is 45 moved in either direction. Since the circuit terminal plate comprising the parts 14 and 15 is a simple punching and since the hollow rivets as well as the cylinder and plunger are cheaply made screw machine 50 products, my entire switch is low in cost. Moreover, the continuous spring-pressed bearing of the plunger against the channel 15 and its intermittent bearing against the head 11 of one of the hollow rivets keeps 55 the contacting parts clean by a wiping action, so that I can readily secure the desired ample conductivity.

However, while I have illustrated and described my invention in an embodiment having 60 certain highly desirable shapes and arrangements of the various parts, I do not wish to be limited to these or other details of the construction and arrangement thus disclosed, it being obvious that many modifications might be made without departing

either from the spirit of my invention or from the appended claims.

I claim as my invention:—

1. A switch comprising an insulating base having a recess therein, a pair of wire terminals extending through the base at opposite ends of the recess, a circuit terminal plate connected to one wire terminal and having a portion thereof disposed within the recess, the other wire terminal having a head overhanging the recess, a switch front extending parallel to the base and having a slot substantially in the longitudinal plane of the recess, and a switching member extending through the slot of the switch front and slideable upon the switch front, the switching member having a conducting portion continuously engaging the said plate portion and yieldingly pressed toward the latter and movable by a sliding of the switching member with respect to the switch front into and out of a position in which it also engages the said overhanging wire terminal head. 70 75 80 85

2. A switch as per claim 1, in which the circuit terminal plate includes a part secured to one circuit terminal and another part offset from the aforesaid part and housed by the recess in the insulating base, the latter part having a portion bowed toward the switch front so as to afford a hump over which the conducting portion of the switching member rides while being moved into and out of its said position, the said hump affording a cam action cooperating with the yielding pressing of the said conducting portion towards the said plate to hold the switching member in either of two positions in only one of which it engages the overhanging wire terminal head. 90 95 100 105

3. A switch as per claim 1, in which the circuit terminal plate comprises a portion resting upon the forward face of the insulating plate and secured to one of the wire terminals, and a channel shaped portion extending into the said recess, the channel shaped portion including a pair of walls laterally engaging the conducting portion of the switching member to prevent movement of the said portion transversely of the said longitudinal plane of the recess, and also engaging the longitudinal walls of the recess to prevent rotation of the said plate about the said wire terminal. 110 115 120

4. A switch comprising a casing having a slot in its front and a back of insulating material parallel to the front, a pair of circuit terminals having portions exposed on the forward face of the said back and spaced from each other in a direction longitudinal of the slot; and a switching member comprising a pair of insulating elements respectively engaging the forward and rear faces of the said front, the forward one of the said elements having a shank extending into 125 130 135

the slot and this shank having flat walls engaging the longitudinal walls of the slot to prevent rotation of the shank with respect to the said front; a rearwardly open cylinder having a forwardly directed threaded stem extending through the rear one of the said elements and threaded into the forward

element, a metal plunger extending through the opening of the cylinder, and a spring in the cylinder continuously urging the plunger rearwardly.

Signed at Chicago, Illinois, December 3rd, 1923.

CHARLES Y. KNIGHT.
